METALLIC BED

Solomon Radtins, Brooklyn, N. Y.

Application December 7, 1936, Serial No. 114,599

9 Claims. (Cl. 5—280)

The present invention relates to a metallic bed construction and it particularly relates to a novel method of combining the panel with the tubular frame of the foot and head pieces of metallic beds.

5 Among the objects of the present invention are to provide an improved panel construction for the head piece and foot piece of metallic beds, in which the panel will be closely united with the frame, although separate therefrom, without the necessity of slotting or otherwise affecting the structural integrity of the frame.

10 Another object is to provide a more artistic head and foot piece construction for metallic beds, in which, although the panel will be unitarily joined to the frames of tubular stock, such junction will not weaken either the panel or frame construction, and may be readily and inexpensively made without detracting from the artistic appearance of the bed and decorative effect thereof.

15 A further object is to provide an improved close attachment of the panel to the foot and head frames of metallic beds, which not only will not detract from the artistic appearance of the bed construction, but in addition will eliminate movement or looseness between the panel and bed frame, and give the bed better sound deadening properties.

20 Other objects will be obvious or will appear during the course of the following specification.

25 In accomplishing the above objects it has been found most satisfactory to form the frame of tubular stock which may consist of welded tubing or rolled-in tubing, preferably squared, but also possibly of other polygonal or circular cross-sections. 30 On this frame, in one embodiment, is attached a U-member having one leg longer than the other, the longest leg being spot-welded to the side of the tube frame.

35 If desired this U may be superimposed upon another U extending inside of the first U, the two U's reinforcing the adjacent side of the frame and affording a most rigid and permanent connection.

40 It also may be desired in certain connections to attach the edge of the panel directly to the frame and then for enhanced strength to turn over the portion of the panel upon the spot-welded connections. These connections between the panel and the frames of the bed not only are of enhanced strength and increased durability, but in 45 addition they lend themselves most desirably to the decorative appearance of the bed giving an artistic border effect.

45 Referring to the drawing which shows several of the embodiments of the present invention by way of illustration, not by way of limitation, since

many modifications and changes may be made, all within the spirit and scope of the present invention.

Fig. 1 is a perspective view of a foot piece of a bed illustrating the panel in position. 5

Fig. 2 is a side sectional view upon the line 2—2 of Fig. 1.

Fig. 3 is a perspective view illustrating the method of connecting the panel to the spot welded holder member as indicated in Figs. 1 and 2. 10

Figs. 4 and 5 illustrate an alternative construction, Fig. 4 being a transverse sectional view of a portion of the frame with the edge of the panel in position and Fig. 5 being a fragmentary constructional perspective view similar to Fig. 3, and 15 showing the method of attaching the U's and panels to the frame.

Figs. 6 and 7 show alternative attachments of the panel to the bed frame.

Referring to Fig. 1, the frame A carries the panel B, which panel is connected to the frame A by the holder construction C. 20

As indicated best in Figs. 2 and 3, the frame A is composed of a square, tubular member, but of course the tubular member may be of other cross sections than shown and be formed in other manners as indicated. 25

Attached to the outside face 10 of the tubular frame A is a long leg or flange 11 of the holder member C. The gripping flange or leg 12 projects inwardly and is approximately parallel to long leg 11, but may also slightly converge toward said flange 11 and its edge. The bend 13 is preferably kept a short distance inside of the outer edge 14 of the wall 10 of the tubular frame A. 30

At intervals the long leg 11 is spot-welded as indicated at 15 to the wall 10 and in the intervals 16 it is substantially unattached to the wall 10. These spot-welds 15 are positioned substantially to the inside of the inner edge 17 of the turned flange 40 portion 12, as shown in Fig. 3.

The edge 18 of the panel B is then readily inserted or slotted into the recess 19 between the flanges 11 and 12 and when the insertion has been completed the flange 12 may be bent or pressed 45 downwardly so that its inner edge 17 grips the panel B inside of the outer edge 18 of the panel.

In the construction as shown in Fig. 1, the panel may be inserted from the bottom of the end piece and the bottom of the panel, as indicated at 20 50 may be turned inwardly and connected to a cross member (not shown) extending between the legs 22 of the frame A so that the panel will be held rigidly in position.

When the piece is painted the paint will cover 55

the contact between the edge 17 and the panel B, so that there will be no open space between the edge 17 and the panel.

The construction as shown in Figs. 1 to 3 is particularly permanent and durable and gives a desirable rigid construction of both the head and foot pieces of the bed.

In addition, the spot-welding connections 15 are relatively few in number and they are 10 readily concealed so as not to disfigure the appearance of the bed.

In the embodiment of Figs. 4 and 5, similarly functioning parts being indicated by the same numerals primed, and additional U member 23' is 15 spot-welded in position as indicated at 24' which causes the outer portion 25 of the flange 11' to be stepped outwardly. The outer portion 25 of the flange 11' will overlie the spot-welding 24.

The flange portion 12', together with the outer 20 portion of the U member C' will press closely down upon the band element 23 as indicated in Figs. 4 and 5. The edge 18' of the panel B' may then be readily inserted in position in the recess 19'. This construction as shown in Figs. 4 25 and 5 also gives especial strength to the bed, enables ready assembly of the panel, and gives a neat and decorative appearance to the head or foot piece of the bed.

In Fig. 6 is shown a construction slightly different from that shown in Fig. 3, similarly functioning parts being indicated by the same numerals and letters provided with a superior 2.

In the embodiment of Fig. 6, however, these 35 spot-welds are positioned inside of said flange 12' instead of outside as shown in Fig. 3.

In Fig. 7 is shown another alternative construction, similarly functioning parts being indicated by the same numerals and letters provided with a superior 3.

40 In this construction the panel B³ is directly spot-welded at 15³ to the frame A³ and the projecting edge of the panel B³ is turned inwardly as indicated at 12³. In this construction the in-turned edge 12³ reinforces the spaced spot-welds 45 15³ to give a most desirable reinforced construction.

45 In all of the embodiments it will be noted that the edges of the panel B are frictionally gripped over a large peripheral area by the holder C which eliminates metallic resonance and also 50 prevents looseness of the panel B in respect to the frame A.

55 This is a much superior construction than one in which the side members are slotted and only grip the panels along the edges of the slot. Moreover it is more durable and gives the bed a better appearance when painted.

60 The invention, however, is not intended to be restricted to any particular construction or arrangement of parts, or to any particular application, of any such construction, or to any specific method of operation, or manner of use, or to any of various details thereof, herein shown and described, as the same may be modified in 65 various particulars or be applied in many varied relations without departing from the spirit and scope of the claimed invention, the practical embodiments herein illustrated and described merely showing some of the various features entering 70 into the application of the invention.

75 What is claimed is:

1. A metallic bed end construction capable of 70 withstanding substantial changes in temperatures without creation of stress and having sound-deadening properties, comprising an in-

verted U-shaped unsplit tubular frame, a sheet metal panel covering said U and extending between the legs and base thereof and devoid of rigid connection to said frame, and a holder for the panel attached to said tubular frame, said holder consisting of a folded metal strip having a flattened U-cross section and spot welded at one side to said tubular frame and said panel being inserted into said fold and being clamped between said folds. 10

2. A bed panel construction comprising an inverted U-shaped tubular frame, a panel covering said U, and a holder for each panel attached to said tubular frame, including two superimposed U-shaped strips, both spot welded to the 15 tubular frame and the outer U-shaped strip receiving and gripping the panel.

3. A bed panel construction comprising an inverted U-shaped tubular frame, a panel connected to said frame, by spot welding and an in-turned flange member overlying said spot welding. 20

4. A bed panel construction comprising an inverted U-shaped tubular frame, a panel covering said frame and having a spot welded connection 25 thereto, and a flanged cover element overlying said spot welding.

5. A bed panel construction comprising an inverted U-shaped tubular frame, a panel covering said frame and connected thereto, and a 30 flanged cover element carrying said panel, said cover element consisting of a folded metallic strip with a long leg and a short leg, the long leg lying against said frame and being spot welded thereto. 35

6. A metallic bed end construction capable of 40 withstanding substantial changes in temperatures without creation of stress and having sound-deadening properties, comprising an inverted U-shaped unsplit tubular frame, a sheet metal panel covering said U and extending between the legs and base thereof and devoid of rigid connection to said frame, and a holder for the panel attached to said tubular frame, said holder consisting of a folded metal strip having a flattened 45 U-cross section and spot welded at one side to said tubular frame and said panel being inserted into said fold and being clamped between said folds, the bend of said fold being substantially inside of the outside edge of said frame. 50

7. A metallic bed end construction capable of 55 withstanding substantial changes in temperatures without creation of stress and having sound-deadening properties, comprising an inverted U-shaped unsplit tubular frame, a sheet metal panel covering said U and extending between the legs and base thereof and devoid of rigid connection to said frame, and a holder for the panel attached to said tubular frame, said holder consisting of a folded metal strip having a flattened U-cross section and spot welded at one side to said tubular frame and said panel being inserted into said fold and being clamped between said folds, said metal strip being folded 60 so as to have a long inside leg and a short outside leg, said long inside leg being the one spot welded to the frame. 65

8. An end construction for metal beds or the like comprising an inverted unsplit tubular U-frame and a pair of vertically and resiliently 70 spaced substantially parallel plates at its periphery forming a smooth-walled marginal recess, and a panel having an edge entering and retained in said recess, said edge being clipped between said parallel plates, which are bent toward each other. 75

and which have a spot welded connection to said frame.

9. An end construction for metal beds or the like comprising an inverted unsplit tubular U-frame and a pair of vertically and resiliently spaced substantially parallel plates at its periphery forming a smooth-walled marginal recess, and

a panel having an edge entering and retained in said recess, said plates constituting the legs of a U-shaped strip, the fold of which is positioned on the outside and the inside leg of which is spot welded to the frame.

SOLOMON RADUNS.
